(57) **CLAIM**

The ornamental design for a hubbed axle, as shown and described.

DESCRIPTION

FIG. 1 is a front perspective view of the hubbed axle embodying my design;

FIG. 2 is a side elevational view of FIG. 1;

FIG. 3 is a left end view of FIG. 1; and,

FIG. 4 is a right end view of FIG. 1.

The broken lines illustrate portions of the hubbed axle that form no part of the claimed design.
